United States Patent Office

Des. 188,755
Patented Sept. 6, 1960

188,755

SIDECAR VEHICLE

Earl S. Fogle, 246 N. Bradoaks, Monrovia, Calif.

Filed May 2, 1960, Ser. No. 60,392

Term of patent 14 years

(Cl. D14—3)

FIG. 1.

FIG. 2.

Fig. 1 is a front perspective view of a sidecar vehicle showing my new design; and

Fig. 2 is a rear perspective view thereof.

The dominant features of my design reside in the portions shown in full lines.

I claim:

The ornamental design for a sidecar vehicle, as shown and as described.
